Linus E. Russell, Springfield, Ohio, assignor to Peters and Russell, Inc., Springfield, Ohio, a corporation of Ohio

Filed July 8, 1964, Ser. No. 80,764

Term of patent 14 years

(Cl. D65—1)

FIG. 1 is a perspective view of a pump embodying my design, showing one side and one end thereof in detail; FIG. 2 is a top view thereof; FIG. 3 is an end view thereof.

It is noted that the far side of the pump as shown in FIG. 1 of the drawings is essentially a mirror image of the side illustrated with the exception of one end thereof, the details of which are clearly evidenced in viewing the lower right hand corner of FIG. 2 and the left side of the pump base as seen in FIG. 3.

I claim:

The ornamental design for a pump, substantially as shown and described.
